HIGH VACUUM DISTILLATION PROCESS
AND APPARATUS

Kenneth C. D. Hickman, Rochester, N. Y., assignor to Distillation Products, Inc., Rochester, N. Y., a corporation of Delaware

Application March 28, 1942, Serial No. 436,646

4 Claims. (Cl. 202—205)

This invention relates to improved high vacuum centrifugal stills and in particular high vacuum stills in which the condensing and vaporizing surfaces both rotate.

High vacuum centrifugal stills are described and are well known in the prior art; see, for instance, my Patent 2,210,927, August 13, 1940. In such stills the distilland is introduced onto the approximate center of a rotating plate and is caused to flow thereover in a thin film by centrifugal force. The vapors are condensed upon the condensing surface which likewise may rotate in which case the condensate on the rotating condensing surface is thrown to the periphery by centrifugal force. It has been proposed to heat such stills by radiation from electrically heated resistance units or by circulation of a heated liquid in contact with the vaporizing surface. It will be realized that heating of a rapidly rotating disc in a high vacuum is a rather difficult problem to solve. The above-mentioned heating expedients have not been completely satisfactory for various reasons. Electricity is a good heating means but it is very expensive; also, the heating resistance units are expensive. When heating with a low vapor pressure liquid it has been found that certain difficulties are encountered due to vapors given off by the heated liquid. They not only tend to lower the pressure in the stills, but also contaminate the materials being distilled.

This invention has for its object to provide a cheap and efficient method of heating high vacuum centrifugal stills. Another object is to provide improved high vacuum centrifugal process and apparatus. A still further object is to provide high vacuum centrifugal stills which can be heated by combustion. Other objects will appear hereinafter.

These and other objects are accomplished by my invention which includes high vacuum distillation process and apparatus in which the condensing and vaporizing surfaces form an integral rotatable unit and are both exposed to approximately atmospheric or higher pressure on one side and a high vacuum on the other side, heat being applied to the vaporizing surface on the side exposed to the atmospheric or like pressure. My invention also includes a rotating high vacuum distillation process and apparatus in which the rotation causes removal of liquids therein against atmospheric pressure.

In the following description I have given several of the preferred embodiments of my invention, but it is to be understood that these are set

forth for the purpose of illustration and not in limitation thereof.

In the accompanying drawings wherein like numbers refer to like parts, I have illustrated two of the preferred embodiments of my invention wherein:

Fig. 1 is a vertical section of a centrifugal still provided with a single vaporizing and condensing surface embodying the principles of my invention.

Fig. 2 is a vertical section of a multi-unit still embodying the improved construction of my invention and

Fig. 3 is a vertical section of a multi-unit still similar to that shown in Fig. 2 but illustrating alternative methods for removal of liquids from the still.

Referring to Fig. 1, numeral 4 designates a circular vaporizing plate the center of which protrudes outwardly at 6. Numeral 8 designates a similarly shaped condensing surface which is integral with vaporizing plate 4 and makes gastight connection therewith at flange 10. Numeral 12 designates a conduit which is connected to the approximate center of condenser 8 and integral therewith. Conduit 12 is rigidly mounted in bearing 14 and supporting bearing 16 in the manner illustrated. Numeral 18 designates a pulley integral with conduit 12 through which power is applied to rotate the conduit 12, condensing plate 8 and vaporizing plate 4 as an integral unit. Numeral 20 designates a stationary conduit which connects to a backing pump (not shown). Numeral 22 designates a flange at the end of conduit 12 which is provided with a ground joint 24. Stationary conduit 20 is likewise provided with a similar ground joint also indicated by numeral 24. Numeral 26 designates a stationary collar fixed to conduit 20 in a gastight manner at joint 27 and is provided with a sealed packing 28. The space between the collar 26 and flange 22 is filled with a low vapor pressure sealing compound.

Numeral 30 designates the casing of a condensation pump. Numeral 32 designates the working fluid and the boiler. Numeral 34 designates the high pressure jet of the condensation pump, and numeral 36 the openings in the chimney 30 through which pump fluid flows into jet 34. Numeral 38 designates the low pressure jet of the condensation pump and numeral 40 the openings through which pump fluid vapors pass from the chimney into the jet 38. Numeral 42 designates an annular gutter mounted upon the inner side wall of conduit 12. Numeral 44 designates

a conduit serving to withdraw liquid from gutter 42 and deliver it into boiler 32. Numeral 46 designates a conduit through which liquid to be distilled is introduced onto the central depressed portion 6 of vaporizing plate 4. Numeral 48 designates an annular flange or collar integral with the inside wall of condenser 8. Numeral 50 designates a conduit provided with a liquid seal which communicates with the space immediately above collar 48 and which terminates in gutter 52. Numeral 54 designates a conduit for withdrawing liquid from gutter 52. Numeral 56 designates a liquid seal conduit which communicates at one end with the inside of the still at a point immediately below flange 48, the other end of which terminates in gutter 58. Numeral 60 designates a conduit for withdrawing liquid from conduit 58. Letter *a* designates the head of liquid which accumulates in the withdrawal conduit 50 and which would be required to force liquid from the still during operation. Numeral 66 designates a plurality of gas burners supplied with gas through conduit 68, the flames impinging upon the outside surface of vaporizing plate 4. Numeral 70 designates a combustion chamber or chimney serving to conserve the heat generated by burners 66 and to remove combustion products.

Referring to Fig. 2, numeral 90 designates an annular collar which joins still units A and B into one integral unit. Stills A and B are constructed in a manner very similar to that illustrated in Fig. 1. Numeral 92 designates an annular gas burner which surrounds collar 90. Numeral 94 designates a furnace or chimney structure of rectangular cross section the walls of which come into close proximity with the outside periphery of stills A and B. Numeral 96 designates a relatively low vapor pressure heating fluid such as mercury.

Referring to Fig. 3, numeral 102 designates a withdrawal conduit to remove undistilled residue from the space between the periphery of the vaporizing surface 44 and the separating collar 48. Numeral 104 designates a withdrawal conduit for removing condensate from the periphery of condensing surface 8. This condensate collects at the periphery and is prevented from mixing with undistilled residue by separating collar 48.

Numeral 106 designates a reciprocating pump connected to conduit 102 and numeral 108 designates a conduit connected to the exhaust side of said pump. Conduit 108 terminates in an annular gutter 110 which is stationary. Numeral 112 designates a withdrawal conduit to remove liquid from gutter 110. Numeral 114 designates a stationary eccentric cam and numeral 116 designates a shaft which is reciprocated by revolving around the stationary eccentric cam 114. This reciprocation actuates pump 106. Numeral 118 designates a reciprocating pump similar to 106, which is similarly actuated by shaft 120 and stationary cam 114. Numeral 122 designates a conduit connecting to the exhaust side of pump 118 and terminating inside stationary gutter 124. Numeral 126 designates a withdrawal conduit for removing liquid from stationary gutter 124.

Numeral 130 designates a rotary pump the intake side of which is connected to conduit 104 and the exhaust side of which is connected to conduit 132. Conduit 132 terminates inside stationary gutter 134 to which gutter is connected a withdrawal conduit 136. Numeral 138 designates a shaft which actuates rotary pump 130. This shaft is provided with a gear 140 at the end

opposite pump 130 which meshes with stationary gear 142. During rotation of the still, gear 140 remains stationary and thus gear 140 is caused to rotate shaft 138 and in turn actuate pump 130. 5 Numeral 146 designates a rotary pump similar to pump 130. The intake side of this pump is connected to conduit 102 and the exhaust side is connected to conduit 148 which terminates inside stationary gutter 150. Numeral 152 designates 10 a withdrawal conduit connected to gutter 150. Numeral 154 designates a shaft which during operation actuates pump 146 by gear 158 meshing with stationary gear 142.

In operating the apparatus illustrated in Fig. 15 1 it is first necessary to introduce sufficient liquid into the still on each side of partition 48 to fill the liquid seal in conduits 50 and 56. The entire still unit is then rotated by force applied to pulley 18. Rotation causes the liquid introduced into 20 the still to fill the liquid lock or sealed portions of conduits 50 and 56. The evacuating pumps are then put into operation. The backing pump (not shown) connected to conduit 20 is first started and then the working fluid 32 in the boiler is 25 vaporized by heat from resistance heater 31. The vapors pass upward through openings 36 and 40 and are then deflected downward through jets 38 and 34. Gases in the still are entrained in these vapor jets and are pushed downward and are 30 eventually removed by the backing pump connected to conduit 20. Condensed vapor from these jets flows into gutter 42 through conduit 44 and thence back into boiler 30.

Liquid to be distilled is introduced through conduit 46 into depressed portion 6 of vaporizing plate 4. The entire surface of plate 4 is then heated by burners 66 to distillation temperature. The liquid flowing through conduit 46 is thrown by centrifugal force in the form of a thin film 40 over the surface of vaporizing plate 4. Undistilled residue flows into conduit 50 and is then flung into conduit 52, the speed of rotation being sufficient to throw the liquid out of the still as explained in detail below. Vapors derived from 45 the film of distilland condense on the inside surface of condenser 8, which is air cooled. This condensate is then flung by centrifugal force to the periphery of plate 8 and is compelled to flow by flange 48 into conduit 56 from which the condensate is thrown into gutter 58 and removed therefrom by way of conduit 60. Undistilled residue accumulates in gutter 52 and is withdrawn by way of conduit 54.

The amount of liquid head which must accumulate in conduit 50 or analogous conduit 56 will 55 depend upon the speed of rotation and the diameter of the still. It is necessary that the centrifugal force applied to the head, i. e., the liquid between the points indicated by the letter *a* Fig. 1 be slightly in excess of the atmospheric pressure. This can be determined in a simple manner by any skilled physicist. For a plate having a diameter of about 32 inches and a speed of rotation of about 1000 R. P. M. a head of about 6 cm. would be desirable although a slightly smaller head could be used.

In operating the apparatus illustrated in Fig. 2, the still unit A and B is rotated by force applied through pulley 18 and the withdrawal conduits 50 and 56 are filled with liquid as described in connection with Fig. 1. Liquid to be distilled is introduced through conduit 46 and burners 92 are put into operation. The stills are evacuated by suitable pumps connected to conduits 20. Distillation takes place as described in connection

with Fig. 1 in both stills A and B. Heating of vaporizing plates 4 takes place by vapors from heating fluid 98 which may be any suitable heat transfer agent such as mercury or diphenyl. These vapors pass into contact with vaporizing plate 4 where they are condensed. The condensate is thrown by centrifugal force against collar 90 where it is again vaporized and returned to the vaporizing plate.

The operation of the apparatus illustrated in Fig. 3 is the same as that of Fig. 2 except for the method of withdrawing distillate and undistilled residue from the still. In Fig. 3 the undistilled residue is withdrawn from still A by pump 106 and from still B by pump 146. Reciprocation of shaft 116 actuates reciprocating pump 106 and withdraws the undistilled residue which is forced into conduit 108 and thence into gutter 110. This undistilled residue flows by gravity to the bottom of gutter 110 and is withdrawn through conduit 112. Rotary withdrawal pump 146 is actuated through conduit 148 into stationary gutter 150 from which it is withdrawn through conduit 152.

Pumps 118 and 130 serve to withdraw condensate from stills A and B respectively. Pump 118 withdraws the condensate through conduit 104 and forces it through conduit 122 into stationary gutter 124 from which it is withdrawn through conduit 126. Pump 118 is actuated by reciprocation of shaft 120 which is caused to reciprocate by traveling over the outside surface of eccentric cam 114 which is stationary. Rotary pump 130 is actuated by rotation of shaft 138 which is caused to rotate by gear 140 meshing with stationary gear 142. The liquid pumped out of the still by pump 130 is forced through conduit 132 into stationary gutter 132. The liquid collecting in gutter 132 is withdrawn through conduit 136.

It will thus be seen that I have provided a high vacuum centrifugal still in which the centrifugal surface is exposed to pressures approximately the same as or greater than atmospheric and in which heating is a simple problem. Application of combustion gases or other cheap heating media can be made without encountering problems heretofore encountered in connection with the supplying of heat to a rotating surface in a high vacuum. The stills can be disposed in series in a tall furnace one above the other; the distilland first being introduced into the top still of the series. This still would naturally be at the lowest temperature and would remove the lowest boiling fraction. The undistilled residue would then flow in sequence down through the stills and would eventually be withdrawn from the still positioned at the lowest point in the furnace which still would be at the highest temperature.

What I claim is:

1. High vacuum centrifugal distillation apparatus comprising vaporizing and condensing surfaces adapted to be rotated as a unit about a common axis and co-operating to form the walls of a vacuum tight still, means for rotating the surfaces in an environment which is at approximately atmospheric pressure, means for applying heat to that side of the vaporizing surface which is at approximately atmospheric pressure, an evacuating port communicating with the space between the vaporizing and condensing surfaces,

means for introducing distilland onto the approximate center of and means for removing residue from the periphery of that side of the vaporizing surface which is not exposed to approximately atmospheric pressure and means for removing distillate from that side of the condensing surface which is not exposed to atmospheric pressure.

2. High vacuum unobstructed path centrifugal distillation apparatus comprising vaporizing and condensing surfaces of circular shape, co-operating to form approximately parallel walls of a vacuum tight unobstructed casing and adapted to be rotated about a common axis, means for rotating the surfaces in an environment which is at approximately atmospheric pressure, means for applying heat to that side of the vaporizing surface exposed to atmospheric pressure, an evacuating port surrounding the axis of rotation for maintaining a high vacuum in the space between sides of the condensing and vaporizing surfaces not exposed to atmospheric pressure, means for introducing distilland onto the approximate center of and means for removing residue from the periphery of that side of the vaporizing surface which is not exposed to atmospheric pressure, and means for removing distillate from that side of the condensing surface which is not exposed to atmospheric pressure.

3. High vacuum unobstructed path distillation apparatus comprising vaporizing and condensing surfaces of circular shape co-operating to form the walls of a vacuum tight still casing and adapted to be rotated about a common axis, means for rotating the surfaces in an environment which is at approximately atmospheric pressure, means for applying hot gases to that side of the vaporizing surface exposed to atmospheric pressure, an evacuating port at the axis of rotation for maintaining a high vacuum in the space between those sides of the condensing and vaporizing surfaces not exposed to atmospheric pressure, means for introducing distilland onto the approximate center of and means for removing residue from the periphery of that side of the vaporizing surface which is not exposed to atmospheric pressure, means for removing undistilled residue from the periphery of the vaporizing surface and means for removing distillate from that side of the condensing surface which is not exposed to atmospheric pressure.

4. A vacuum centrifugal still having a vaporizing surface and condensing surface, means for maintaining a vacuum between said surfaces, means for heating the vaporizing surface, means for cooling the condensing surface, means for introducing distilland onto the vaporizing surface, and means for removing condensate from the condensing surface said still being characterized by rotatable condensing and vaporizing surfaces which co-operate to form the walls of the casing of the still, which surfaces are exposed to substantially atmospheric pressure on one side, and during operation, to a vacuum on the other side and over which distillate and distilland respectively are caused to flow as a film by centrifugal force and further characterized by means for applying heat to the side of the vaporizing surface which is at atmospheric pressure.

KENNETH C. D. HICKMAN.
